ARTHUR MUTSCHELLER, OF NEW YORK, N. Y., AND CARL JOHAN LARSEN, OF EAST ORANGE, NEW JERSEY, ASSIGNEES TO WAPPLER ELECTRIC COMPANY, INC., OF LONG ISLAND CITY, NEW YORK, A CORPORATION OF NEW YORK

CYSTOSCOPIC X-RAY TABLE

Application filed May 25, 1926. Serial No. 111,479.

Our invention relates to cystoscopic X-ray tables of the type in which a seat is provided for the patient, in order to enable him to recline or sit up, as the case may be, while being examined cystoscopically as to the condition of certain organs, and also while said organs are being exposed to the action of X-rays, as for instance in making radiographs.

Our improved table is specially constructed and arranged for use in the examination and treatment of the genito-urinary tract, and various organs and parts immediately associated therewith.

An important feature of our improved apparatus is its facility to enable radiographic examinations to be made of various organs, such for instance, as the kidneys, the patient first occupying one position and then being moved into a different position, so that the precise location of the organs, with the patient resting in one position, can be contrasted with the location of the organs when the patient is resting in a different position.

More particularly stated, we seek to improve the cystoscopic X-ray table by connecting with it a rocking board, so formed and arranged as to admit of tilting to different degrees independently of the general inclination of the table as a whole, and adapted to serve as a seat for supporting all or practically all of the patient's weight when the patient is sitting up, and to support a smaller proportion of the patient's weight, varying with the position of the patient, as he reclines or is raised or lowered into different recumbent positions.

It has heretofore been customary, in radiographing various organs and parts of the human body, to employ a cystoscopic table carrying the X-ray tube, together with an X-ray plate holder or cassette, and an X-ray filter. This X-ray filter is instrumental in reducing the undesirable secondary radiation. It has also been customary to so construct and arrange the apparatus as a whole that when the table, with the patient resting thereupon, is tilted to different angles in order to bring the patient's body into different degrees of inclination, the X-ray tube, the X-ray plate and the X-ray filter are thereby automatically

brought into new positions corresponding to those into which the table is thus tilted.

As is well known in this art, it is usually difficult to make good radiographic examination of various internal organs, because such organs are very transparent to X-rays. It is therefore customary to inject into organs of this character a small quantity of a solution which is relatively opaque to the X-rays. This has practically the effect of rendering the organs visible, or at least discernible during the X-ray examination and places them in suitable condition for taking radiographic pictures. For X-ray examination of the kidneys, and for diagnosis of strictures of the ureters, as well as for studying changes in the positions of the kidneys relatively to other parts of the body, it is the usual practice to inject the opaque solution by means of one or more catheters, and this is most conveniently done by using in connection with such catheters some appropriate form of catheterizing cystoscope.

It has recently become known that often-times useful data as to the condition of the kidneys and various other internal organs here contemplated may be obtained by contrasting the position of the organs, while the patient occupies one position, with the relative position of the same organs when the patient occupies a different position; for instance, to first observe the location of the kidneys while the patient occupies a reclining position, and then by way of contrast to note the relative location of the kidneys while the patient sits upright.

However, in making examinations of this kind, under conditions where the observations are to be made by aid of X-rays and the results are to be shown upon radiographs, a practical difficulty has arisen. When the kidneys are to be shown upon the radiograph, and when for this purpose the aforesaid solution opaque to X-rays is injected into the kidneys and tubular passages leading thereto, it often happens that the patient, by exerting himself in shifting from one position to another, causes muscular contractions to take place in parts immediately adjacent the kidneys; and these muscular con-

tractions may expel all or a considerable portion of the opaque fluid from the kidneys. It is therefore in practice necessary to reduce to a minimum all necessity for the patient to make any muscular exertion, at least after the opaque fluid has been injected and before the radiographs have been taken.

A very important purpose of our invention is to so improve the cystoscopic table, by adapting it for use with our improved rocking seat, that by its aid the patient may be readily shifted from one position to another, as for instance from a recumbent position to a sitting position, without the exertion of any muscular effort on his part for the purpose. In other words, we so arrange our rocking board and so connect it with the table, that the patient lying on the table and resting partly upon our improved rocking board may be easily, slowly and gradually raised from a reclining position to a sitting position, without any exertion upon his part, and without any danger of sliding obliquely downward, no matter to what angle of inclination the table as a whole may be tilted.

By means of our table with its rocking board, the kidneys and various other organs can be radiographed so as to disclose not only their form and general condition, but also to reveal any dropping or other displacement in their position relatively to other parts of the body, as the patient is shifted from one bodily position to another. It frequently happens that disease of an organ such as a kidney, or disease of the various ligaments, membranes, arteries, veins and the like leading to and connected with the organ, may be readily detected by noting changes in the relative position of the organ as the patient is shifted from one position to another. Sometimes a very slight displacement of an organ such as a kidney gives a clue as to the presence and character of some disease of the organ or parts immediately associated therewith.

Our rocking board is provided with a main or body portion cut away or provided with a large opening of suitable form to promote accessibility, by the operator, to various organs of the patient which are to be examined or treated by aid of our invention.

Reference is made to the accompanying drawings forming a part of this specification, and in which like reference characters indicate like parts throughout the several figures.

Figure 1 is a side elevation of our improved cystoscopic X-ray table, with its rocking board, all arranged to support a patient resting in a recumbent position, parts of the mechanism being broken away.

Figure 2 is an end elevation of the mechanism, certain parts being broken away.

Figure 3 is a section on the line 3—3 of

Figure 1, looking in the direction indicated by the arrows.

Figure 4 is a detail of the gearing shown in the left hand portion of Figure 2, certain parts being broken away.

Figure 5 is a section on the line 5—5 of Figure 4, looking in the direction indicated by the arrows.

Figure 6 is a side elevation of the table, and shows in dotted lines the patient resting upon it in a recumbent position, this view indicating the relative positions of the X-ray tube, the X-ray plate holder and the X-ray filter relatively to various portions of the table and the patient resting thereupon.

Figure 7 is a side elevation showing the position of the table with the X-ray tube, the plate holder, and various movable parts, with the patient resting upon the table, but occupying a position different from the one he occupies in Figure 6.

Figure 8 is a side elevation indicating the positions of the X-ray tube and plate holder and various movable parts of the table relatively to the patient, who here occupies a sitting position.

Figure 9 is a detail showing the X-ray filter and mechanism for actuating the same, but upon a larger scale than that of Figure 8.

Figure 10 is a plan view of the rocking board.

A pair of side frames 9 and 10 are connected by cross bars, one of which is shown at 11, and these side frames are mounted upon castor rollers 12, 13.

The back board of the table appears at 14, and connected with it are a pair of hanger arms exactly alike, one being shown at 15. This back board 14 is provided with a suitable top portion 16 which supports the patient's back when the patient occupies a reclining position during an examination. Extending into each of these two arms is a screw bolt 17, provided with a head 18, shown more particularly in Figure 3.

Encircling the bolt 17 is a sleeve 19, which serves as a journal neck and extends through a bearing 20 with which the side frame 9 is provided, and also through a bearing 21, as may be understood from Figure 3.

The bearing 21 is carried by a supporting plate 22. This supporting plate extends vertically from this bearing 21, and adjacent its lower edge is provided with a bracket portion 22' constituting a bearing for a pair of horizontal swinging supporting bars to be herein-after referred to. There are two of these supporting plates 22, each of the form shown, and each provided with a slot 24 and with notches 25 merging into this slot, as may be understood from Figures 1, 2 and 3. The notches 25 serve as bearings, and as there are two supporting plates 22, each provided with these notches, there are of course two sets of bearings. Resting in the notches thus

serving as bearings are a pair of pintles 26, each of the form shown in Figure 3. The pintles 26 support a rocking board 27 provided with a pair of bearings one of which is shown at 28, each pindle 26 extending through one of these bearings and being secured rigidly thereto, as indicated in Figures 2 and 3. Supported upon the rocking board 27 are a pair of floor boards 29, which are used for matting and serve to vertically increase the height of the rocking board 27, the latter thus being practically adjustable as to height. Either or both of the floor boards can be removed, so that the patient may sit either upon the rocking board 27 or upon one or more of the floor boards carried thereby.

The rocking board 27 is cut away, so as to leave an edge portion 30 of arcuate form as shown in Fig. 10. This shape is for promoting accessibility to the organs of the patient by the operator, for purposes of examination and treatment.

The rocking board may be easily shifted into a number of different positions by raising it slightly, so as to lift the journal pins 26 from the notches in which they happen to rest, the rocking board being then slightly shifted and lowered so as to bring the journal pins into other notches 25, as may be understood from Figure 1.

Thus the mountings which support the rocking board are movable back and forth, within reasonable limits permitted by the spacing of the notches.

The rocking board 27 carries a pair of lugs 31, preferably integral with it, and adapted to engage another pair of lugs 32, with which the supporting plates 22 are provided. By this arrangement the rocking board 27 is given a certain amount of freedom to rock, but this movement is limited by the engagement of the lugs 31 with the lugs 32. The net result is that the outer or free edge of the rocking board 27 can be raised into the position indicated for it by dotted lines in Figure 1, but can not be lowered beyond the position indicated for it by full lines in this figure; or in other words, only far enough to render the general plane of the rocking board substantially horizontal, as indicated in Figure 1 a plate 33 serves as an end wall, and to some extent conceals mechanism located below the table.

The back board 14 carries a casing 34, having substantially the form of a flat box which is disposed between the back board 14 and the top portion 16.

Detachably fitted into one side of the casing 34 by aid of a slot 35, is a plate holder or cassette 34a, carrying a photographic sensitized plate 34b, as indicated in Fig. 9. Movably located within the upper portion of the casing 34 is an X-ray filter 34c, supported upon rollers one of which appears at 34d, the latter engaging a pair of rails one of which

is shown at 34e. The X-ray filter thus supported is movable back and forth for the purpose of wiping out the secondary rays during a radiographic exposure. A suitable driving motor such as an electric or spring motor (not shown) is arranged to drive a pair of friction engaging conical pulleys 34f. A shaft 34g extends from one of these conical pulleys and is provided with a pinion gear 34h, the latter of which engages a worm gear 34i.

This latter worm gear is arranged to drive a small drum 34j and a small cable, a portion of which is shown at 34k, encircles this drum. The cable 34l passes around the drum 34j and around a pair of small idle pulleys 34m disposed at each end of the casing 34. The free ends of the cable 34k are secured to each side of the X-ray filter 34c and, depending upon the direction of rotation of the motor, the filter is moved in one direction or the other longitudinally of the back board 14 and top portion 16. A pillow board 36 is utilized for supporting the head and shoulders of a patient and is adjustably arranged by the provision of a pair of rack bars 37 which are pivotally secured to the pillow board.

Pivotaly connected with the back board 14 are a pair of rack bars 39, 40, substantially alike, and each operated in a manner which may be understood from Figures 4 and 5. The rack bar 39 is engaged by a pinion 41 mounted as indicated in Figure 5. The pinion 41 is mounted upon a shaft 42 and has relatively wide teeth which are engaged by a worm 43, the latter being fixed rigidly upon a shaft 44 extending nearly the full width of the table. The shaft 44 carries a collar 45 and a hub 46, the hub carrying a hand wheel 47 by the rotation of which the shaft 44 may be turned. Thus the operator by turning the hand wheel 47 can cause the racks 39, 40 to be slowly raised and lowered, and by doing this can cause the back board 14 and parts carried thereby to swing bodily upon the bearings 20, 21.

The back board 14 carries a tube column 48, and supported by this column is an X-ray tube and a number of parts 50. The purpose of this is to enable the operator to bring the X-ray tube 49 into different positions of adjustment relatively to the tube column 48 and to other parts.

The parts 50 are so adjusted as to bring the X-ray tube 49 into alignment with the cassette 34a, so that an imaginary line extending from the X-ray tube to the cassette is perpendicular to the face of the cassette, and thus perpendicular to the sensitive plate carried by the cassette; and also to the general plane of the X-ray filter.

Mounted upon the brackets 22' of the members 22, and journaled to swing horizontally in relation thereto are a pair of supporting bars 52, and adjustably mounted upon these

supporting bars are a pair of supporting rods 53, which are adjustable relatively to the supporting bars 52. Carried upon the supporting bars 52 are a pair of leg supports 54, 55, for the purpose of supporting the patient's legs by engaging the under side thereof at points adjacent the knees.

The operation of our device is as follows:

10 The patient is placed upon the table, his head and shoulders resting upon the pillow board 36 and his back resting upon the top portion 16. In this position his seat is upon a rocking board 27, his legs extending over the leg supports 54 and 55. If desirable the foot stool or equivalent support may be used for sustaining the weight of his feet, and the table can be so tilted as to incline downwardly at the head; that is, into the Trendelenburg position.

20 The operator now examines the patient as above described, and for this purpose may employ any form of cystoscope or endoscope suitable for the purpose.

25 If the kidneys or any other organs adjacent thereto are to be examined by aid of X-rays, the organ or organs to be examined are first treated as above stated with a solution more or less opaque to X-rays. These steps having been taken and the X-ray tube and other parts having been properly adjusted, the X-ray tube is energized and at the same time the X-ray filter is operated, and a radiograph is taken in the manner well known in this art.

35 If, now, it be desired to take a second radiograph with the patient occupying a different position, say for instance sitting upright, the operator merely actuates the hand wheel 47. This raises the back board 14 as indicated in Figure 7, the movement being continued, if required, until the patient sits upright, as indicated in Figure 8.

40 This is done without the necessity for the patient moving a muscle, the net result being that the opaque solution remains in the kidneys, and the kidneys are therefore maintained in condition to be photographed by means of the X-rays.

45 As may be seen by comparing Figures 6, 7 and 8, the changes noted in the position of the movable parts of the table, and in the position of the patient as he is shifted from a recumbent position to a sitting position, are accomplished without disturbing the relative location of the X-ray table, the cassette or plate holder, the X-ray filter with its operating mechanism, or any of the parts of the table which are shifted along with the patient. The single exception is the rocking board 27, 50 which as above described can make a slight rocking movement in one direction, but can not exceed a certain predetermined limit of travel in the opposite direction; or in other words, the rocking board becomes fixed when 55 it reaches a horizontal position.

The patient being in a sitting position, one or more additional radiographs may be taken, and these radiographs, or pictures copied from them, may afterwards be contrasted with the corresponding radiographs or pictures previously taken with the patient in a recumbent position.

By contrasting the two sets of radiographs or pictures made therefrom, any drop or dislocation of the kidneys due to the shifting of the patient's body can be readily detected and the patient's condition as affected thereby may be determined accordingly.

We do not limit ourselves to the precise mechanism shown, as variations may be made therein without departing from our invention, the scope of which is commensurate with our claims.

We claim:

1. A device comprising a table frame, a pair of supporting plates mounted upon said table frame and extending upwardly therefrom, said supporting plates being each provided with a plurality of notches serving as bearings, and a rocking board provided with journal pins for removably fitting into said notches and thus supporting said rocking board while allowing said rocking board to rock.

2. A device comprising a frame, a back board journaled thereupon, a pillow board carried by said back board and adjustable relatively thereto, mechanism connected with said frame and with said back board and controllable by the operator for shifting said back board to different angular positions relatively to said frame, a rocking board adjustably journaled upon said frame and movable to various angular positions independent of the movements of said back board, an X-ray tube carried by said back board and movable relatively thereto to enable said X-ray tube to maintain a predetermined normal position relatively to said back board when said back board is shifted relatively to said frame, and means for supporting an X-ray plate within said back board.

3. A device comprising a table frame, a table top carried by said table frame and mounted to tilt relatively thereto, supporting plates mounted upon said table frame, and a rocking board mounted with said supporting plates, said rocking board and said supporting plates being provided with means for enabling said rocking board to be detachably journaled upon said supporting plates in a plurality of different positions relatively to said table frame.

4. A device comprising a table frame, a table top carried by said table frame and adjustable relatively thereto, an X-ray filter carried by said table top, a pair of supporting plates mounted upon said table frame and extending upwardly therefrom, a rock-

ing board pivotally mounted upon said supporting plates and free to rock relatively to said table frame, an X-ray tube carried by said table top and having a predetermined fixed position relatively to said table top carrying said X-ray filter.

5. A device comprising a table frame, a table top tiltably mounted on said table frame, supporting plates mounted upon said table frame and each provided with a plurality of bearings, a rocking board provided with pintles for engaging said bearings, said pintles being removable from one pair of said bearings to another pair thereof in order to enable said rocking board to be shifted bodily from one position to another relatively to said supporting plates, an X-ray tube, an X-ray filter and mechanism for actuating said X-ray filter, all carried by said 20 table top, so that said X-ray filter may be kept focused upon said X-ray tube independently of the tilting of said table top, and means for limiting rocking movements of said rocking board relatively to said supporting plates.

6. A device comprising a table frame, a table top mounted upon said table frame and adjustable relatively thereto, mechanism connected with said table top and controllable by the operator for shifting said table top relatively to said table frame, a plate holder carried by said table top and normally occupying a fixed position relatively thereto, an X-ray tube, an X-ray filter and mechanism for actuating said X-ray filter, all carried by said table top, and a rocking board connected with said table frame and serving as a seat for a patient, said rocking board being movable independently of the inclination 40 of the table top.

7. A device comprising a table frame, a table top journaled upon said table frame, mechanism connected with said table top and table frame and controllable by the operator for shifting said table top into different angular positions relatively to said table frame, a plate holder carried by said table top, mechanism carried by said table top for supporting an X-ray tube in a predetermined normal position relatively to said plate holder, an X-ray filter carried by said table top and movable therewith as said table top is shifted into said different angular positions relatively to said table frame, and a 50 rocking board detachably supported upon said table frame and adjustable bodily into different positions relatively thereto, said rocking board being free to rock in each of its said different positions, and means for limiting the rocking movement of said rocking board.

ARTHUR MUTSCHELLER.
CARL JOHAN LARSEN.
